MEANS FOR ADMITTING AIR TO A FIRE BOX

Nathan M. Lower, Baltimore, Md., assignor to
The Standard Stoker Company, Incorporated,
a corporation of Delaware

Application June 11, 1931. Serial No. 543,555

4 Claims. (Cl. 110—101)

This invention pertains to the improvement in the structure of appliances adjacent the firing opening of a firebox, and particularly to improvement in the construction of parts thereof which 5 form closures for the firing opening, which are exposed to the heat of the firebox, and are air cooled; such as, firedoors and the delivery end of a stoker.

One of the objects is to permit entrance of air 10 through the firing opening into the firebox above the elevation of the firebed for the purpose of cooling the fuel distributing apparatus of a stoker and firedoors, and to prevent emission of gases and other elements of the firebox through 15 the firing opening by providing a one way valve or damper in the air passageways actuated by the draft and products of combustion in the firebox to automatically open and close the passageways.

20 With the present method of cooling firedoors and the distributor plate of a stoker relatively cold air is drawn through holes in the firedoors and through a passageway between the lower margin of the firing opening and stoker parts, 25 respectively, by the draft in the firebox, and in the event of minor explosions and other disturbances in the firebox from some unforeseen defect or reason, such as caused by the breaking of an arch pipe or water tube in the case of a firebox 30 of a boiler, gases, flaming cinders, smoke, steam and hot water are discharged through the firing opening causing damage and probably injury to persons in the vicinity thereof; and it is a further object of this invention to provide a construction that will correct this undesirable feature and prevent damage and casualties in the case such disturbances occur.

Other objects, advantages and novel details of construction will be apparent during the course 40 of the following description taken in connection with the accompanying drawing, in which:

Fig. 1 is a vertical sectional view taken on the center line of a stoker firing opening of a stationary firebox and a portion of a stoker, showing 45 one form of the invention as applied thereto.

Fig. 2 is a vertical transverse sectional view of the structure shown in Fig. 1, taken on line 2—2 thereof.

Fig. 3 is a vertical longitudinal sectional view 50 taken on the center line of a common hand and stoker firing opening of a locomotive firebox showing a firedoor and a portion of a stoker with parts thereof broken away, illustrating a modified form of the invention as applied thereto.

55 Fig. 4 is a vertical transverse sectional view of

the structure shown in Fig. 3, taken on line 4—4 thereof, with parts omitted.

Fig. 5 is a vertical sectional view of a firedoor equipped with this invention, and is partly dia- 60 grammatic.

In Figures 1 and 2, the numeral 1, designates a brick wall of a firebox of the stationary boiler, heating plant, and steamboat type; 2, the stoker firing opening therein; and 3, the stoker as a whole. Inserted in the firing opening 2 is an oval shaped metal ring 4 for supporting the bricks above the opening and preventing the bricks adjacent the opening from becoming loose. The ring 4 is provided with an outwardly extending flange 5 by which it is secured to the outside of the firebox wall. A stoker conduit 6 is butted against the flange 5, in alignment with the top margin of the ring 4, and is secured thereto. A jet plate casting 7 is supported upon the lower margin of the ring 4 and secured to the stoker 75 conduit so as to form a continuation of the lower inside surface of the conduit. The jet plate 7 has fluid nozzles 8 at the firebox end thereof in communication with a cored chamber 9. The cored chamber 9 extends transversely of the jet 80 plate at the firebox end thereof and along the sides of the jet plate, as is apparent in Fig. 2. The cored chamber 9 communicates with a source of pressure by means of suitable piping (not shown), which is well known in the art. A distributor table 10 is positioned in the firebox 11, beneath and immediately forward of the fluid nozzles 8, and supported on the laterally projecting rib 12. Fuel is transferred through the conduit 6 by any suitable means, here shown as a 85 helical screw, and is delivered into the path of the fluid blasts, issuing from the nozzles 8, onto the distributor plate 10, from which it is discharged to all parts of the firebed. Fuel directing means may be employed to govern the flow 90 of the fuel to the nozzles 8, such as hinged vanes 13. The positions of these vanes are controlled manually by hand wheels 56.

Between the lower margin of the ring 4 and the underside of the jet plate 7, and centrally thereof, is an air passageway 14 extending from the outside of the firebox to the inside. The passageway 14 is angular in shape, the portion 15 thereof extending through the firing opening being horizontal; and the portion 16, which is outside of the firebox, being vertical. The jet plate 7 is provided with three downwardly extending walls 17 which form the vertical portion 16 of the air passageway.

Positioned in the passageway 14 is a one way 110

valve or damper 18, which is hinged to the under-side of the jet plate 7. The damper 18 is arranged to swing only in a direction to admit relatively cold air into the firebox. Stops 19 on the 5 sides 20 of the passageway prevent the damper from swinging in a direction to allow emission of elements from the firebox.

When the firebox has a fire therein the variation in pressure on opposite sides of the damper 18, due to the draft in the firebox, causes the damper to swing toward the inside of the firebox and air enters the passageway 14 at the outside end thereof, is drawn through the firing opening, and directed to impinge upon the stoker parts 15 that are exposed to the heat, for cooling the said parts. If a disturbance occurs in the firebox, causing the pressure on the firebox side of the damper to become equal to or greater than atmospheric pressure on the outside of the 20 damper, the damper will close and prevent the escape of elements of the firebox through the passageway; and in case of a minor explosion the damper will snap shut. If a small percentage of the discharge should get past the damper, the 25 walls 17 will direct the discharge downwardly.

Referring to Figures 3 and 4, the numeral 21 represents the firebox of a locomotive; 22, the back wall of the firebox having a common hand and stoker firing opening 23 therein; 24, the fire-door; 25, the locomotive cab; 26, the cab deck; and 27 the stoker as a whole. The firedoor 24 is attached to the backhead and closes the upper portion of the firing opening 23. The stoker 27 has laterally projecting flanges 28, by which it is rigidly secured to the backhead in the well known manner with studs 29 extending through these flanges; and it is apparent that the stoker closes the remainder of the firing opening 23 beneath the firedoor.

The stoker structure shown in Figures 3 and 4 is similar to that illustrated in Figures 1 and 2. The transfer conduit portion 30 of the stoker extends upwardly through the cab deck 26 and has its outlet end opening inside the firebox. A 45 distributor table 31 is positioned in the firebox and secured to the forward end of the stoker. Fluid nozzles 32, at the rear of the distributing table 31, are in communication with cored chambers 33 and a source of pressure as described in 50 regard to Figures 1 and 2. Any preferable form of conveying means may be employed to convey and deliver fuel into the path of the fluid blasts issuing from the nozzles 32, and hinged vanes 34 may be used to direct the flow of fuel to the fluid 55 blasts.

The transfer conduit portion 30 of the stoker is spaced from the lower margin of the firing opening 23 sufficiently to provide an air passageway 35 from the outside to the inside of the firebox. 60 The passageway is angular in shape, the rear portion 36 of which is parallel to the outside of the backhead. The passageway 35 is formed by the side walls 37, front and rear walls 38, and top and bottom walls 39 and 40, respectively. Top wall 39 also forms a part of the transfer conduit portion 30. The side walls 37 and the front and rear walls 38 form the rear portion 36 of the air passageway which extends below the cab deck 26.

Hinged on a horizontal axis in the passageway 70 35 is the valve or damper 41. It is provided with adjustments 42 so that the weight thereof beneath the axis about which it rotates can be made slightly greater than the weight of the portion above its axis. Thus, the damper will always 75 maintain a vertical position unless there is a draft

in the firebox and the pressure in the inclined portion 43 of the air passageway is less than atmospheric pressure on the outside of the firebox. If the damper 41 is in its vertical position the passageway 35 is closed.

When the locomotive boiler is in operation the draft in the firebox 21 causes the damper 41 to move to its open position (shown in dotted lines in Fig. 3) in the same manner as described in regard to Figures 1 and 2, and relatively cold air enters the passageway 35 beneath the elevation of the cab deck, is drawn through the passageway, and directed by the shape of the passageway to impinge on the distributor table 31 and other stoker parts exposed to the heat, for cooling the same. If from any cause whatsoever, the pressure in the inclined portion 43 of the passageway becomes greater than the air pressure in the rear portion 36, the damper will immediately return to its vertical or closed position and prevent passage of elements from the firebox to the outside. Should a small percentage of the discharge leak past the damper 41, it will be directed downwardly beneath the cab deck; thus, probable injury to the fireman and engineer, and damage to apparatus 100 in the cab is prevented.

It will be advantageous in some instances to regulate the amount of air that is admitted through the firing opening, as cold air admitted above the firebed causes inefficient combustion. To obtain this result a plurality of holes 44 are drilled radially about the axis of the damper, and a pin 45, which can readily be withdrawn, is inserted in any one of the holes so that the desired amount of air will be admitted to cool the 110 parts exposed to the heat. The pin 45 acts as a stop for the damper and limits the open position thereof.

In Figure 5 the numeral 46 designates the back wall of a firebox; 47, the firing opening therein; 115 and 48, the firedoor as a unit. The firedoor 48 comprises the fluid pressure actuated motor 49, the main body portion of the firedoor 50, the perforated renewable baffle plate 51, and the baffle plate securing bolt 52. Provided in the body 120 portion of the firedoor, near the upper end thereof, is an opening or passageway 53. Pivoted in the body portion 50, adjacent the upper end of the passageway 53, is a valve or damper 54 similar to the damper 41 shown in Figures 3 and 4. A 125 stop 55 limits the open position of the damper 54.

When there is a fire in the firebox the variation in pressure on opposite sides of the damper 54 causes it to open and admit air to the passageway 53 to cool the baffle plate 51 and other parts 130 of the firedoor exposed to the heat. When the pressure on the inside or firebox side of the firedoor is equal to or greater than atmospheric pressure on the outside, the damper 54 will maintain a vertical position and close the passageway 53; thus preventing any discharge from the firebox escaping through the firing opening.

Although I have shown and described what I believe is the preferred embodiment and installations of my invention, I do not want to be limited to the construction or applications shown and described, except insofar as I have included such limitations within the terms of the following claims.

What I claim as new and desire to secure by 145 Letters Patent is:

1. In combination, a furnace having an upright wall provided with a firing opening, a floor extending horizontally outwardly from said wall below the level of said opening, a stoker con-

duit mounted externally of the furnace and communicating with said opening, fuel distributing means associated with the forward end of said conduit, said conduit arranged with the lower 5 marginal edge of the firing opening to provide a space therebetween, and a casing surrounding said space interposed between said conduit and the upright wall of the furnace and extending downwardly to said floor, said casing providing 10 a passageway open only at its opposite ends, the one end opening adjacent the lower rearward end of said fuel distributing means and the other end opening to atmosphere below said floor, whereby the draft in the furnace will draw a current 15 of air through said casing for cooling the forward end of said stoker conduit and said fuel distributing means. 20

2. In combination, a locomotive having a firebox provided with a backwall having a firing 25 opening, a cab floor rearward of said backwall, a stoker conduit mounted externally of the firebox and communicating with said opening, fuel distributing means associated with the forward end of said conduit, said conduit arranged with the lower marginal edge of the firing opening to provide a space therebetween, and a casing surrounding said space extending through the cab floor, said casing providing a passageway open 30 only at its opposite ends, the one end opening adjacent the lower rearward end of said fuel distributing means and the other end opening to atmosphere exteriorly of the cab, whereby the draft in the furnace will draw a current of air through said casing for cooling the forward end 35 of said stoker conduit and said fuel distributing means.

3. In combination, a furnace having an upright wall provided with a firing opening, a floor extending horizontally outwardly from said wall 40 below the level of said opening, a stoker conduit mounted externally of the furnace and communicating with said opening, fuel distributing means associated with the forward end of said conduit, 45

said conduit arranged with the lower marginal edge of the firing opening to provide a space therebetween, a casing surrounding said space interposed between said conduit and the upright wall of the furnace and extending downwardly to said floor, said casing providing a passageway open only at its opposite ends, the one end opening adjacent the lower rearward end of said fuel distributing means and the other end opening to atmosphere below said floor, whereby the draft in the furnace will draw a current of air through said casing for cooling the forward end of said stoker conduit and said fuel distributing means, and a damper for preventing the outward discharge of elements from the furnace 90 through the passageway.

4. In combination, a furnace having an upright wall provided with a firing opening, a stoker conduit mounted externally of the furnace and communicating with said opening, fuel distributing means associated with the forward end of said conduit, said conduit arranged with the lower marginal edge of the firing opening to provide a space therebetween, a casing surrounding said space interposed between said conduit and the upright wall of the furnace to provide an angularly shaped passageway open only at its opposite ends, the one end opening adjacent the lower rearward end of said fuel distributing means and the other end opening to atmosphere exteriorly of the furnace, whereby the draft in the furnace will draw a current of air through said casing for cooling the forward end of said stoker conduit and said fuel distributing means, and a damper in the passageway for preventing the outward discharge of elements from the furnace 100 through the passageway actuated when there is a variation of pressure on opposite sides thereof, said damper being mounted to swing about an axis intermediate its ends and arranged to assume a vertical position to close the passageway. 105
